UNITED STATES PATENT OFFICE.

MELVILLE D. JONES, OF SOMERVILLE, MASSACHUSETTS.

DESIGN FOR A SHELF-BRACKET.

SPECIFICATION forming part of Design No. 20,233, dated October 21, 1890.

Application filed September 19, 1890. Serial No. 365,563. Term of patent 7 years.

To all whom it may concern:

Be it known that I, MELVILLE D. JONES, a citizen of the United States, residing at Somerville, in the county of Middlesex and State of Massachusetts, have invented and produced a new and original Design for Shelf-Brackets, of which the following is a specification, reference being had to the accompanying drawings, forming part thereof.

10 In the accompanying drawings, Figure 1 is a side elevation of a shelf-bracket showing my design. Fig. 2 is an edge view.

The leading feature of my design consists in a semi-elliptical strut and a circular figure tangential to said strut and likewise to the arms of the bracket.

In said drawings, A is the shelf-arm, and B the wall-arm of the bracket, which is of the usual triangular shape.

20 C is the connecting-arm or strut, which is semi-elliptical in curvature and ornamented in relief along its front edge with a diamond-link chain.

Within the triangle formed by the bracket I have positioned a circular figure D, which is tangential to both arms and likewise to the strut. This figure is formed with an interior scalloped periphery produced by a concentric series of semicircular open recesses E. The arms A B have ribs F F upon their inner faces, while the sides of said ribs are paneled or carved for purposes of ornamentation.

What I claim is—

The design for a shelf-bracket herein shown and described, the same comprising the two straight arms A B with inside paneled ribs, a connecting semi-elliptical strut C, and the circular figure D, tangential to said arms and strut and with a scalloped interior periphery, as set forth.

In testimony whereof I affix my signature in presence of two witnesses,

MELVILLE D. JONES.
